UNITED STATES PATENT OFFICE

WALLACE MACGREGOR, OF BERKELEY, CALIFORNIA

SAFETY FIRE HOSE HOLDER

Application filed March 9, 1927. Serial No. 173,806.

This invention resides in the provision of a simply constructed, collapsible, portable, small, compact, light, strong, durable and efficacious means for holding a fire hose in such manner that one operator can safely and easily play the hose in both horizontal and vertical planes with little or no effort.

A single fire hose through which a high pressure stream is passed usually requires from three to five men to hold and properly manipulate the nozzle, but with the present invention one operator may safely and easily manipulate the nozzle in a most effective manner, thereby providing for a saving of time and labor, and eliminating the injury hazard in the fighting of fires.

One of the advantages of the invention is the provision of a portable, light and collapsible holder which may be quickly and easily set up for operation and when not in use may be collapsed into small compass and readily and conveniently stored or carried.

Another object is to provide a means whereby the nozzle may be easily, quickly and safely attached to and removed from the holder, which means permits the nozzle to be turned freely and easily in vertical and horizontal planes to properly direct the stream of water in fighting a fire.

Another object of the invention is to provide a fire hose holder of the character described which has a novel base that permits of simple construction, the employment of but few parts, and provides for secure, stable supporting of an upright standard on which is carried the means for clamping the fire hose to the holder.

A further object of the invention is to provide a fire hose holder of the character described in which by means of a simple adjustment, the play pipe may be stationarily held in various positions without requiring the attendance of the operator.

With the above mentioned and other objects in view, the invention consists in the novel construction and combination of parts hereinafter described, illustrated in the accompanying drawings, and set forth in the claims hereto appended, it being understood that various changes in the form, proportion,

size and minor details of construction within the scope of the claims may be resorted to without departing from the spirit or sacrificing any of the advantages of the invention.

Referring to the drawings:

Fig. 1 represents a vertical sectional view of the holder of my invention as when set up ready for use, the hose being omitted.

Fig. 2 represents a fragmentary horizontal sectional view taken through the collapsible base.

Fig. 3 represents an enlarged vertical sectional view taken at right angles to the view shown in Fig. 1, and showing the hose and nozzle clamped on the holder.

Fig. 4 represents a fragmentary top plan view of the means for clamping the hose.

Fig. 5 represents a side elevation of the holder as when collapsed.

The embodiment of the invention shown in the accompanying drawings comprises generally an especially constructed collapsible base 1, supporting a take-down sectional upright standard 2, which latter carries at its upper end an especially constructed pivoted means 3 for clamping the coupling of the hose and nozzle upon the holder, which means is constructed so that it may be held stationary in any one of several positions of adjustment of the nozzle in a vertical plane. This means together with the standard, provides generally speaking, a safe swivel mounting for the fire hose and nozzle at the juncture thereof and provides for a wide range of movement of the nozzle in vertical and horizontal planes. These elements of my holder are so constructed and relatively arranged that when a flexible fire hose having been coupled to the discharge end thereof in the usual manner, a play pipe or nozzle is clamped on the holder at the coupling of the nozzle and hose, a single operator may safely and with little or no effort direct the stream from the nozzle as required, with greater ease and facility than can three or more operators without the holder of this invention.

The especially constructed base 1 comprises a plurality of arms 4 which are carried by and at the lower end of the sectional standard 2, 100

and project radially outward therefrom, there being a plurality of downwardly and outwardly projecting feet 5 on the outer ends of these arms, which feet are pointed and adapted to engage the ground or other surface on which the holder is mounted in such manner as to firmly anchor the holder against slipping thereon.

The standard 2 comprises an inner tubular section 6 telescoped and adapted to turn freely within an outer tubular section 7, which latter carries a plurality of pairs of spaced apertured ears 8 between which the inner terminals of the arms 4 are hinged by means of pins 9. Extending upwardly from the inner ends of the arms 4 are projections 10 which extend along the outer side of the tubular section 7 in engagement therewith and limit the movement of the arms so that they extend substantially horizontally from the lower end of the standard. A flanged collar 11 surrounds and is slidably mounted upon the standard 2 in such manner that the upward projections 10 may be engaged between the standard and flange 12 of the collar, thereby holding the arms 4 in properly extended position to support the standard. It will be noted that the co-acting faces of the flange 12 and projections 10 are inclined so as to fit snugly and produce a wedging action and thereby prevent accidental displacement of said parts. The standard 2 is provided in its sections 6 and 7 with registering openings 13 disposed in such a position that when a pin 14 attached by a flexible element 15 to the collar 11 is inserted through said openings, the collar will be held against moving upward out of position when the arms are collapsed. The base may be collapsed by lifting the collar 11 clear of the upper projections 10 and thereby permitting the arms 4 to swing into substantially upright position hanging downward from the lower end of the standard. In this position as shown in Fig. 5, the projections 10 extend outwardly laterally from the sides of the standard and by lowering the collar so that the flange 12 thereof engages the upper sides of these projections and inserting the pin 14 in the openings 13, the collar will again be held in such position as to prevent the arms from swinging on their pivots, thereby holding the arms in collapsed position. When the arms are in this position, the entire holder is reduced to a compact form, so that it may be conveniently stored and carried.

The arms 4 are provided with sockets 16 in which rods 17 are held by means of fastening elements 18, the rods extending laterally outward from the ends of the arms and serving as extensions thereof. The outer ends of these rods carry the feet 5 which are provided by bending the outer terminals of the rods downward and pointing them. The arms 4

may be covered with insulation material as shown at 19 to prevent electric currents passing down the water stream from injuring the operator when he steps upon or otherwise comes in contact with the base.

The inner tubular section 6 of the standard 2 is provided at a point between its ends but nearer to its upper end with an annular shoulder 20 which engages the upper end of the outer tubular section 7 and limits the downward movement of the inner section to the extent that its lower end is disposed substantially flush with the outer section. The inner section is enlarged as at 21 at its upper end and is bifurcated as at 22, there being provided opposed plate-like portions 23 between which the clamping means 3 is mounted so that it may be freely turned in a vertical plane.

The clamp 3 is in the form of a sectional circular band comprising two sections 24 and 25 of which the section 24 is provided at its terminals with plate-like portions 26 corresponding to the portions 23 and engaged therewith. These portions 23 and 26 are provided with registering openings 27 and 28 of which the ones 28 are screw threaded. Pivot bolts 29 are inserted through the openings 27 and 28 and are provided with screw threads on their free ends which threads cooperate with threads in the openings 28. On tightening these pivot bolts, the clamping means 3 may be held in any one of its adjusted positions thereby providing for holding the play pipe in the desired position when thus adjusted, although ordinarily these bolts provide for securing the clamp so that it may be freely turned in a vertical plane. The outer section 25 is hinged as at 30 at one end to one end of the section 24. At its other end this section 25 is provided with an outwardly opening slot 32 adapted to receive a threaded bolt 33, hinged at one end as at 34 to the corresponding end of the section 24. A nut 35 is turned on the outer end of this bolt 33 and is adapted to bear against the slotted terminal of the section 25 to effect the clamping action. This bolt may be swung freely into and out of the slot 32 when the nut 35 is loosened. The clamp is especially constructed to receive and hold a standard type coupling 36 which is used to connect the nozzle or play pipe 37 with the flexible hose 38, it being necessary to provide in the lower section 24 an opening 39 of sufficient size to receive different sized lugs 40 such as are provided on said coupling. The upper section 25 is provided with an elongated slot 41 adapted to receive a similar lug 42 carried by said coupling 36 on the side thereof opposite the lug 40. The sections of the clamp are of such a width as to securely and firmly clamp the coupling without in any way interfering with the operation of screw-

ing the nozzle into or unscrewing it from the coupling.

With the holder arranged as shown in Fig. 1, to attach the hose, the clamp is opened and the coupling 36 is placed in the lower section 24 after which the upper section 25 is brought down upon the upper side of the coupling and clamped by means of the bolt 33 and nut 35. The operator then by grasping the play pipe or nozzle and in some instances bending the flexible hose adjacent the nozzle with the knee, may freely turn the nozzle in a horizontal plane, due to the rotation of the inner section 6 of the standard within the outer section 7. The pivotal mounting of the clamp provides for free vertical movement of the nozzle. With this arrangement, a single operator may safely and with little or no effort direct a stream of water as desired in fighting a fire. The lines of force resulting from the re-action of the water discharging from the nozzle pass downward through the stand and are evenly distributed in such manner as to increase the stability of the holder. When a shut off type of nozzle is employed, the stand will support the hose and nozzle in proper position when the water is shut off at the nozzle. If desired, the operator may on tightening the pivot bolts 29, hold the clamp against pivotal movement in a vertical plane and thereby hold the nozzle in any one of several adjusted positions. When thus clamped, the operator need not hold the nozzle inasmuch as it will be stationarily and securely held in the desired position. If desired to prevent horizontal turning of the nozzle, the pin 14 may be inserted in the openings 13 as shown in Fig. 3, thus preventing rotation of the inner section 6 of the standard.

I claim:

1. A safety fire hose holder comprising a base, an upright standard rotatably and adjustably mounted upon the base, a sectional circular clamp pivotally mounted upon the upper end of the standard and adapted to clamp around the coupling member which connects the nozzle with a flexible fire hose, said clamp conforming to the outline of the juncture between the fire hose and the nozzle, said clamp having openings therein conforming to projections of said coupling for locking the same.

2. A safety fire hose holder comprising a tubular upright member, a horizontally extending base upon which said upright member is mounted, a standard rotatably mounted upon the upright member and a clamp pivoted on a horizontal axis upon said standard, which clamp is adapted to surround and interlock with the coupling member of the fire hose and its nozzle, said clamp comprising a supporting jaw pivoted on the standard and a complementary jaw pivoted on said supporting jaw, said jaws conforming to the

outer periphery of the juncture of the fire hose with the nozzle and having openings therein to interlock with projecting portions of said coupling.

3. A safety fire hose holder comprising an upright tubular member, a plurality of radially extending arms pivotally mounted upon the lower end of the tubular member, upright projections on the inner ends of said arms engaging said upright member and acting as stops to limit the movement of said arms in one direction, a flanged collar surrounding and being vertically adjustable on said tubular member, the flange of which is adapted to engage said upright projections, means for holding said collar against vertical adjustment on the upright member, a standard rotatably mounted in said tubular upright member and being adapted to pivotally support a hose clamp on the upper end thereof.
